UNITED STATES PATENT OFFICE.

CURT WILLIAM GOEBEL, OF CHRISTMAS, ARIZONA.

DESIGN FOR A TEA-KETTLE, DOUBLE BOILER AND DISTILLER.

52,951.

Specification for Design.

Patented Feb. 4, 1919.

Application filed September 21, 1918. Serial No. 255,195. Term of patent 14 years.

To all whom it may concern:

Be it known that I, CURT W. GOEBEL, a citizen of the United States of America, residing at Christmas, in the county of Gila and State of Arizona, have invented certain new and useful Improvements in Design of a Tea - Kettle, Double Boiler, and Distiller, of which the following is a specification, reference being had therein to the accompanying drawings.

Figure 1 is a top plan view of my combined tea-kettle, double boiler and distiller, showing my new design.

Fig. 2 is a bottom plan view of my tea-kettle, double boiler and distiller, while

Fig. 3 is a view in side elevation of the same.

Fig. 4 is a vertical sectional view of my tea-kettle, double boiler and distiller.

I claim—

The ornamental design for a tea-kettle, double boiler and distiller, as shown.

In testimony whereof I hereunto affix my signature.

CURT WILLIAM GOEBEL.
